ARTICLE OF FURNITURE

Edward J. Hughes, Bettendorf, Iowa

Application January 24, 1952, Serial No. 267,997

2 Claims. (Cl. 312—239)

My invention relates to an article of furniture combining a writing desk, a dresser or bureau, and a shelf designed particularly to economize space in hotel rooms, apartments and similar rooms.

The objects of my invention are to provide a writing desk with stationary, well lighted writing table combined with a bureau or dresser having curved knee room under the front middle portion of the table and provided with drawers extending the full length of the desk, a series of upper drawers comprising one or more small right and lefthand drawers with a larger intermediate drawer, and a shelf above the table for a mirror, radio, books or other articles; to provide a plurality of full length drawers and an intermediate upper drawer recessed and inwardly curved at the front to allow ample room for the knees of the user. Other objects will appear from the description.

I accomplish these objects by the means illustrated in the accompanying drawings, in which,

Figure 1 is a front elevation of my piece of furniture; Figure 2 is a top or plan view;

Figure 3 is a horizontal section on the line 3—3 of Figure 1;

Figure 4 is an end view.

Similar numerals refer to similar parts throughout the several views.

My article comprises a top plate or table 1 extending the full length and depth of the article, supported by end pieces 2—2 which may have the top of the ends curved as shown in Figure 4.

Mounted upon suitable supports 3 carried by the ends are the drawers 4—4 which extend the full length between the ends. The front edges of the drawers when closed are in line with crossbars 3—3 the ends of which are united to the end pieces 2 and the middle portions of which are curved to the rear on the lines shown in dotted lines in sectional view Figure 3.

The two lower drawers are preferably made full length but with recessed middle portions following the dotted lines of Figure 3 as corrected. Between the two lower drawers and the table top 1, an intermediate drawer 13 is mounted approximately one-third as long as the two lower drawers and at each side of this intermediate drawer small drawers 7—7 may be installed.

Upon the upper crossbar 3 vertical supports 6 are mounted the upper ends of which are rigidly secured to the table 1 at the front thereof.

One or more small drawers 7 may be mounted between the table 1 and the upper crossbar 3 and be carried by the upper supports 3.1 which extend from the corresponding crossbar 3 to the rear or back plate 8 of the article. The ends 2 may extend upwardly above the table

2

as at 2.1 and small additional drawers 9 may be mounted on the table.

A shelf 10 may be mounted near the top of the ends 2 and arranged to hold a mirror, radio, books or other articles as desired.

The back plate 8 may extend even with or below the lower crossbar 3 with legs 11 united to the side plates extending downwardly below the back plate and provided with casters or sliders of any desired kind. A vapor lamp 12 is preferably mounted upon the back plate 8 under the shelf 10.

This article of furniture may be made entirely of wood or metal or a suitable plastic or partly of one or more of those materials as manufacturing conditions and the public demand make most advisable.

Various modifications may be made in the size, depth or curvature and other particulars without departing from the spirit of my invention as expressed in the claims and I do not limit my claims to the precise forms shown in the drawings.

I claim:

1. As an article of manufacture, a combination bureau and writing desk in compact form, including vertical end and back support pieces of the desired height, a rectangular table top mounted upon the end pieces and back at convenient height, a plurality of flat supporting bars carried by the ends in spaced position below the table top, a plurality of drawers slidably mounted upon the supporting bars, both the drawers and the front supporting bars having semi-circular recesses provided therein extending from the front toward the rear approximately one-third of the depth of the drawers, the lower drawers extending the full length of the table and being covered when closed, and the drawer next to the table top being shorter and occupying approximately one-third of the length of the table top at the middle thereof and with a plurality of small drawers mounted at opposite ends of and adjoining the shorter drawer.

2. As an article of manufacture, a condensed bureau and writing desk in compact form, including end and back pieces, supporting a rectangular table top mounted thereon, a plurality of flat transverse bars in spaced position below the table top to carry drawers slidably mounted thereon, both the drawers and the front supporting bars having central semi-circular recesses provided therein extending from the front toward the rear approximately one-third of the depth of the drawers, the lower drawers extending the full length of the table and the drawer next to the table top being shorter and occupying approximately one-third of the length of the table top at the middle thereof.
